Primary Examiner — Patricia Palasik(74) *Attorney, Agent, or Firm* — Price Heneveld LLP(57) **CLAIM**

I claim the ornamental design for a guillotine-type cutting machine, as shown and described.

DESCRIPTION

FIG. 1 is a front elevational view of a guillotine-type cutting machine, showing my new design; and, FIG. 2 is a perspective view thereof.

The broken lines are directed to environment and are for illustrative purposes only; the broken lines form no part of the claimed design.
